[57] CLAIM

The ornamental design for a fan fold photograph display card, as shown.

DESCRIPTION

FIG. 1 is a front perspective view of a fan fold photograph display card showing my new design in an unfolded configuration;

FIG. 2 is a top plan view thereof, of which the bottom plan view is a mirror image;

FIG. 3 is a front view thereof;

FIG. 4 is a rear view thereof;

FIG. 5 is a left side elevational view thereof, of which the right side elevational view is a mirror image;

FIG. 6 is a front perspective view thereof in a folded configuration;

FIG. 7 is a top plan view thereof, of which the bottom plan view is a mirror image; and,

FIG. 8 is a left side elevational view, of which the right side elevational view is a mirror image.
